UNITED STATES PATENT OFFICE

2,689,032

KEY OPERATED MECHANISM FOR TYPE-WRITING OR LIKE MACHINES

Reynold Earl Wheeler, Farmington, Conn., assignor to Royal Typewriter Company, Inc., New York, N. Y., a corporation of New York

Application August 6, 1952, Serial No. 302,885

10 Claims. (Cl. 197—176)

1

This invention relates to key operated mechanism for typewriting or like machines, and more particularly to mechanism of the class referred to, including two key members operable selectively for actuating an instrumentality to be operated.

One object of the invention is to provide mechanism of this class in which the key members are provided respectively with hand engageable portions so relatively positioned and combined as to facilitate operation of the instrumentality by a selected one of the key members, the selectivity of operation and the positioning of the hand engageable portions of the key members enabling the user to operate the instrumentality with maximum ease and speed and with a minimum of hand movement.

Another object of the invention is to provide mechanism of the character stated, in which the hand engageable portions include a finger engageable portion on one key member and a palm engageable portion on the other key member, the palm engageable key lever being so arranged that it may be operated quickly by a slight tilting or turning of the hand without its being necessary to move the hand substantially from left to right of the machine.

Another object of the invention is to provide an improved mechanism of the kind referred to, in which the key levers are so constructed that operation of one transmits movement to the other, the latter in turn transmitting movement to the instrumentality to be operated.

A further object of the invention is to provide an improved tabulating mechanism.

Other objects of the invention will become apparent from a reading of the following description, the appended claims, and the accompanying drawings, in which:

Figure 1 is a fragmentary vertical sectional view fore and aft of a typewriter embodying the invention, some parts being shown in elevation, key mechanism being shown in full lines in its normal or non-actuated position.

Figure 2 is a fragmentary view similar to Figure 1 but showing parts of the key mechanism in their actuated positions.

Figure 3 is a fragmentary top plan view of the key mechanism as seen when looking in the direction of the arrow 3 in Figure 1.

Figure 4 is a fragmentary vertical sectional view of the rear part of a typewriter illustrating the improved tabulating mechanism, some parts being shown in elevation; and

Figure 5 is an exploded perspective view show-

2

ing the relation of certain parts of the tabulating mechanism.

The typewriting mechanism shown by way of example as embodying the invention in a preferred form is generally similar in many respects to the Royal standard office typewriter and the Royal electric typewriter. It includes a main frame element A provided with a lower track or rail 1 on which a carriage element B, includ-

10 ing end plates 2 and 3, is mounted for horizontal letter spacing and return travel by means of a carriage or top rail 4 and ball rollers, one of which is shown at 5 in Figure 4. The carriage B is equipped with the usual cylinder or platen C.

15 The carriage B is urged to the left, that is, in the letter spacing or typing spacing direction, by suitable means such as a conventional spring drum (not shown) which exerts a steady pull on a draw band connected by a clip 6 to an ear 7

20 on the right hand carriage end plate 2. Movement of the carriage to the left under the urge of the spring drum or other driving mechanism is governed by feed controlling mechanism, as shown an escapement mechanism including a

25 rack 8 carried by an angle bar or rail 9 having rearwardly extending arms 10 pivotally mounted on the carriage at 11. Springs 12, connected to rearwardly extending portions of the arms 10

30 and anchored at 13 on the carriage, normally hold the escapement rack 8 in the position shown in Figure 4, in which the rack meshes with an escapement pinion 14 journaled on a shaft 15 carried by a frame-mounted bracket 16. The pinion 14 is fast with an escapement wheel 17

35 adapted to rotate about the shaft 15 and to cooperate with suitable escapement pawls or dogs (not shown). In operation, when the escapement dog mechanism is actuated, the wheel 17 is permitted to turn in step-by-step increments so as to permit the rack 8, and, consequently, the carriage to be fed to the left in the direction of typing.

40 Key mechanism embodying the present invention may be used for operating various instrumentalities but is especially useful for operating tabulating mechanism, some parts of which may be of known construction and arrangement. Con-

45 ventional or known tabulating mechanism parts shown in the drawings include a support generally designated 18 mounted on the carriage and comprising upper and lower rack bars 19 and 20 respectively formed with transverse grooves

50 21, 22 which register with each other and which are spaced longitudinally of the rack bars at letter space intervals.

55

Mounted on the stop frame or support 18 is a plurality of laterally settable tabular stop parts, one of which is designated 23 and is shown in its normally inoperative position, and the other of which 23' is shown in its rearwardly projected or operative position. The tabular stop parts 23-23' are similar to individual stops disclosed in the patent to Myers et al. No. 1,892,071, issued December 27, 1932. Each includes a bridge or central portion 24, upper lugs 25 and 26, which project alongside opposite sides of the upper rack bar 19, and lower lugs 27 and 28 which project downwardly alongside opposite sides of the bottom rack bar 20. Each tabular stop part is provided with a spring 29 mounted on a pin 30, with one end hooked at 31 around the edge of the tabular stop just above the lug 27, the other end of the spring being curved as at 32 so as to press against the top rack bar 19. The arrangement is such that each tabular stop can be shifted transversely of the frame 18 to an operative position at 23' or to an inoperative position shown at 23, the spring 29 frictionally and yieldably maintaining the stop in whichever position it has been set.

The support 18 serves also to assist in mounting the carriage B for travel on the frame A. A bracket 33, secured to the lower toothed bar 20, is provided at its lower end with a roller 34 adapted to run on a channel track 35 carried by the main frame A. The roller and bracket 33 thus support the rear of the carriage B which is supported at its front by the track rails 1 and 4 and the balls 5.

Also of known construction is a center stop lever 36 cooperable with margin stops (not shown) on the carriage for limiting the carriage travel and thus determining the right- and left-hand margins on work sheets. The center stop is pivoted at 37 on a frame-mounted bracket 38 and can be swung to move its upper end rearwardly and out of the path of the margin stops for margin releasing. A line lock lever 39 is pivoted at 40 on the center stop lever 36 and is adapted to be connected in a known manner to mechanism for preventing depression of the typewriter keys when the carriage reaches its line end position.

The improved tabulating mechanism includes a tabular stop blade or finger device 41 fixed to a hub 42 adapted to rock on a shaft 43 carried by the bracket 38. A spring 44 interposed between a stud 45 on the finger 41 and an ear 46 on a fixed bracket 47 urges the finger 41 to rock clockwise, as viewed in Figure 4, to its normal or retracted position in which it is disposed out of the path of any operatively positioned tabular stop 23' on the carriage B. The finger 41 may be rocked counterclockwise by improved mechanism, to be described, so as to position its upper end portion in the path of an operatively positioned stop 23' on the carriage.

In order to enable the carriage to perform a tabulating run, which will be arrested by engagement of an operatively positioned stop 23' with the stop finger 41, it is necessary to disable the feed controlling mechanism to render the carriage free to be moved toward the left by the driving mechanism. For this purpose a disabling lever 48 is pivoted at 49 on the bracket 16 and is provided with an upper arm 50 secured to which is a pressure block 51 underlying the escapement rack angle bar 9. When the disabling lever 48 is rocked clockwise, as viewed in Figure 4, the pressure block 51, which normally

is disposed below and out of contact with the angle bar 9, is raised so as to lift the angle bar 9 and the attached escapement rack 8, thereby disengaging the latter from the escapement pinion 14. Disengagement of the rack 8 from the pinion 14 disables the escapement mechanism and enables the carriage driving mechanism to move the carriage uninterruptedly toward the left so as to perform a tabulating run which will be terminated by engagement of the operatively positioned stop 23' with the operatively positioned stop finger 41.

Since, as is apparent from the foregoing, it is necessary to disable the feed controlling mechanism and move the stop finger 41 to its operative position simultaneously in order to effect a tabulating run of the carriage, mechanism is provided for causing the stop finger 41 to be moved to its actuated position when the disabling lever 48 is rocked to lift the escapement rack 8. As shown in Figures 4 and 5, a link connection 52 is pivoted at 53 to the disabling lever 48 and is pivoted at 54 to the stop finger 41. It is important that the movements of the disabling lever 48 and the stop finger 41 be related and determined precisely in order to ensure efficient and dependable operation. Accordingly, the link 52 is constructed so as to be readily adjustable and, as shown, it includes two link parts 52^a and 52^b, the part 52^a being provided with slots 52^c adapted to receive screws 52^d having threaded engagement with the link part 52^b. The screw and slot connection provides for easy and accurate adjustment of the length of the link 52, enabling the timing of movement and the relative positioning of the disabling lever 48 and the stop finger 41 to be determined within close limits.

Mechanism for rocking the disabling lever 48 includes a rock shaft 55 mounted on a bracket 56 and an operating arm or lever 57 fast on the shaft 55 and having its upper end rounded, as shown at 58, and disposed immediately behind a depending pad 59 on the disabling lever 48. Another arm 60, also fast on the shaft 55, is pivoted at 61 to the rear end of a link, generally designated 62, the front end of which is pivoted at 63 to a lever 64 pivoted on the main frame at 65. A forwardly projecting arm 66 of the lever 64 extends under a cushion 67 carried by a frame cross bar 68, the cushion determining the upward movement of the lever arm 66 to its normal or non-actuated position. The link 62 is constructed so as to be adjustable in length and is shown as including two connected link parts 62^a and 62^b, the part 62^a being formed with slots 62^c which receive screws 62^d having threaded engagement with the link part 62^b.

When the lever 64 is rocked counterclockwise, the link 62 is pulled forwardly so as to rock the arm 60, the shaft 55, and the arm 57 counterclockwise. This causes the rounded part 58 of the arm 57 to press against the pad 59 and rock the disabling lever 48 clockwise to raise the escapement rack 8 and disengage it from the escapement pinion 14. Simultaneously, the link 52 will be moved forwardly to rock the tabulating finger 41 from the normal or inactive position shown in full lines in Figure 4 to the position shown in dotted lines in which it is disposed in the path of the operatively positioned tabular stop 23' on the carriage.

An important feature of the invention resides in the key mechanism for operating the lever instrumentalities 64, which in the present instance is

shown associated with the tabulating mechanism. Figures 1, 2, and 3 show two selectively operable key members arranged for convenient manipulation at maximum speed and with flexibility, enabling the operator to operate the key mechanism selectively by using a finger in the normal manner or, in certain instances when more convenient, by merely tilting the hand to effect the key operation by pressure of the palm or side of the hand.

In the form shown, a key lever 69 is pivoted at its front end at 70 on a bracket 71 secured to the frame A by screws 72. A roller 73 journalled on the rear of and projecting laterally from the key lever 69 overlies the lever arm 66. The key lever 69 is provided with a key top or finger engageable portion 74. When the key lever 69 is depressed by the application of finger pressure to the key top 74, the roller 73 depresses the front end of the lever arm 66 so as to rock the lever 64 counterclockwise and to pull the link 62 forwardly, thus effecting a tabulating run of the carriage in the manner previously described.

Another key lever 75 has its rear end pivoted at 76 on the bracket 71. The front end of the key lever 75 provides a driving surface 77 which overlies a driven roller 78 carried by and projecting laterally from the key lever 69. The key lever 75 is provided with a palm engageable key top portion 79. When the key lever 75 is depressed or rocked counterclockwise its driving part or surface 77 drives the roller 78 on the key lever 69 downwardly so as to rock the key lever 69 clockwise and operate the lever instrumentality 64.

A spring 80 interposed between an arm 81 on the key lever 75 and a stud 82 on the frame urges the key lever 75 clockwise to its normal position determined by engagement of a stop part 83 on the key lever 75 with a fixed guide plate 84 carried by the frame cross bar 68. Raising of the key lever 69 is limited by engagement of a stop part 85, formed on the lever 69, with the rear part of the bracket 71.

As will be clear from inspection of Figures 1, 2, and 3, the finger engageable portion 74 on the key lever 69 is of relatively small area as compared to the palm engageable portion 79 on the key lever 75. The palm engageable portion 79 is elongated, with its longer dimension extending fore and aft of the machine, and the portions 74 and 79 are arranged contiguously and substantially in a general plane inclined upwardly and rearwardly from the front of the machine; and the hand engageable portions 74 and 79 are located between the key lever pivots 70 and 76. This arrangement has been found to be especially conducive to facile and rapid operation of typewriters when performing such operations as typing bills on forms, requiring frequent type key operations interspersed with tabular operations. In performing such work, the tabular mechanism may be operated by the palm or side of the hand by merely tilting the hand, without requiring such bodily left-to-right movement of the hand as would remove the fingers from the letter or numeral key area of the keyboard.

The mechanism disclosed embodies the invention in a preferred form, but it is intended that the disclosure be illustrative rather than definitive. The invention is defined in the appended claims.

I claim:

1. In a typewriter or like machine, an instrumentality to be operated; a first key lever extending fore and aft of the machine; a pivot mount-

ing the front of said first key lever on the machine; means on the rear of said first key lever operatively connecting the latter to said instrumentality; a second key lever extending fore and aft of the machine; and a pivot mounting the rear of said second key lever on the machine, a part on said first key lever underlying a part on said second key lever whereby depression of said second key lever will effect depression of said first key lever.

5 2. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

15 3. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

20 4. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

25 5. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

30 6. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

35 7. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

40 8. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

45 9. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

50 10. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

55 11. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

60 12. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

65 13. In a typewriter or like machine, an instrumentality to be operated; a first key lever extending fore and aft of the machine; a first pivot mounting the front of said first key lever on the machine; means on the rear of said first key lever operatively connecting the latter to said instrumentality; a second key lever extending fore and aft of the machine; a second pivot spaced rearwardly from said first pivot and mounting the rear of said second key lever on the machine, a part on said first key lever underlying a part on said second key lever whereby depression of said second key lever will effect depression of said first key lever; and hand engageable portions respectively on said key levers and both being located between said pivots, said hand engageable portions being selectively manually actuatable for effecting operation of said instrumentality.

70 14. Mechanism as set forth in claim 4 in which the instrumentality to be operated is part of a tabulating mechanism.

75 15. In a typewriting or like machine, a frame; a carriage mounted on said frame for letter spacing and return travel; means for driving said carriage in the latter spacing direction; feed

controlling mechanism for normally causing said carriage to be fed by said driving means in incremental letter spacing steps, said feed controlling mechanism including a member adapted to be moved from a normal position in which it renders said feed controlling mechanism operative to a shifted position in which said member is disabled and said feed controlling mechanism is rendered inoperative whereby to release said carriage and enable it to perform a tabulating run; a disabling lever pivoted on said frame and being engageable with said member for moving the latter from its normal position to its shifted position; a pad on said disabling lever; a shaft; an operating lever on said shaft having a rounded portion contactable with said pad for rocking said disabling lever upon rocking of said operating lever; a tabular stop part on said carriage; a tabular stop device movably mounted on said frame and normally being positioned out of the path of said tabular stop part but being movable into an operative position in the path of said tabular stop part for arresting the carriage at the end of a tabulating run; a connection between said disabling lever and said tabular stop device for moving the latter to its operative position when said disabling lever is moved to its shifted position; and key operated means for rocking said operating lever.

7. In a typewriting or like machine, a frame; a carriage mounted on said frame for letter spacing and return travel; means for driving said carriage in the letter spacing direction; feed controlling mechanism for normally causing said carriage to be fed by said driving means in incremental letter spacing steps, said feed controlling mechanism including a member adapted to be moved from a normal position in which it renders said feed controlling mechanism operative to a shifted position in which said member is disabled and said feed controlling mechanism is rendered inoperative whereby to release said carriage and enable it to perform a tabulating run; a disabling lever pivoted on said frame and being engageable with said member for moving the latter from its normal position to its shifted position, a pad on said disabling lever; a rock shaft mounted on said frame; a first arm fast on said rock shaft and having a rounded portion contactable with said pad for rocking said disabling lever upon rocking of said shaft and said first arm; a tabular stop part on said carriage; a tabular stop device movably mounted on said frame and normally being positioned out of the path of said tabular stop part but being movable into an operative position in the path of said tabular stop part for arresting the carriage at the end of a tabulating run; a link interposed between and operatively connecting said disabling lever and said tabular stop device for moving the latter to its operative position when said disabling lever is moved to its shifted position; a second arm fast on said rock shaft; and key operated means for rocking said second arm.

8. In a typewriting or like machine, a frame; a carriage mounted on said frame for letter spacing and return travel; means for driving said carriage in the letter spacing direction; feed controlling mechanism for normally causing said carriage to be fed by said driving means in incremental letter spacing steps, said feed controlling mechanism including an escapement pinion journalled on said frame and an escapement rack mounted on said carriage and adapted to be moved from a normal position in which it engages

5 said pinion to a shifted position in which it is disengaged from said pinion and said feed controlling mechanism is rendered inoperative whereby to release said carriage and enable it to perform a tabulating run; a disabling lever pivoted on said frame and being engageable with said rack for moving the latter from its normal position to its shifted position; a pad on said disabling lever; a rock shaft mounted on said frame; a first arm fast on said rock shaft and having a rounded portion contactable with said pad for rocking said disabling lever upon rocking of said shaft and said first arm; a tabular stop part on said carriage; a tabular stop finger pivotally mounted on said frame and normally being positioned so as to position said end portion thereof out of the path of said tabular stop part but being rockable so as to position said end portion in the path of said tabular stop part for arresting the carriage at the end of a tabulating run; a two part adjustable length link interposed between and connecting said disabling lever and said tabular stop finger for rocking the latter when said rock shaft and said disabling lever are rocked; a manually operable key; a second arm fast on said rock shaft; and a two part adjustable link interposed between and operatively connecting said key and said second arm.

9. In a typewriting or like machine, a frame; a carriage mounted on said frame for letter spacing and return travel; means for driving said carriage in the letter spacing direction; feed controlling mechanism for normally causing said carriage to be fed by said driving means in incremental letter spacing steps, said feed controlling mechanism including a member adapted to be moved from a normal position in which it renders said feed controlling mechanism operative to a shifted position in which said member is disabled and said feed controlling mechanism is rendered inoperative whereby to release said carriage and enable it to perform a tabulating run; a disabling lever pivoted on said frame and being engageable with said member for moving the latter from its normal position to its shifted position; a pad on said disabling lever; a shaft; an operating lever on said shaft having a rounded portion contactable with said pad for rocking said disabling lever upon rocking of said operating lever; a tabular stop part on said carriage; a tabular stop device movably mounted on said frame and normally being positioned out of the path of said tabular stop part but being movable into an operative position in the path of said tabular stop part for arresting the carriage at the end of a tabulating run; a connection between said disabling lever and said tabular stop device for moving the latter to its operative position when said disabling lever is moved to its shifted position; means including an instrumentality operatively connected to said operating lever; two key levers operatively connected to said instrumentality and respectively having hand engageable portions for selective manual actuation of said key levers with consequent operation of said instrumentality; and means mounting said key levers so that when they are in their normal non-actuated positions their hand engageable portions are aligned, contiguous, and substantially in the same general plane.

10. In a typewriting or like machine, a frame; a carriage mounted on said frame for letter spacing and return travel; means for driving said carriage in the letter spacing direction; feed controlling mechanism for normally causing said

carriage to be fed by said driving means in incremental letter spacing steps, said feed controlling mechanism including a member adapted to be moved from a normal position in which it renders said feed controlling mechanism operative to a shifted position in which said member is disabled and said feed controlling mechanism is rendered inoperative whereby to release said carriage, and enable it to perform a tabulating run; a disabling lever pivoted on said frame and being engageable with said member for moving the latter from its normal position to its shifted position; a pad on said disabling lever; a shaft; an operating lever on said shaft having a rounded portion contactable with said pad for rocking said disabling lever upon rocking of said operating lever; a tabular stop part on said carriage; a tabular stop device movably mounted on said frame and normally being positioned out of the path of said tabular stop part but being movable 10 into an operative position in the path of said

tabular stop part for arresting the carriage at the end of a tabulating run; a connection between said disabling lever and said tabular stop device for moving the latter to its operative position when said disabling lever is moved to its shifted position; means including an instrumentality operatively connected to said operating lever; a first key lever operatively connected to said instrumentality; a second key lever; a driving part on said second key lever; and a driven part on said first key lever engageable by said driving part whereby actuation of said second key lever will actuate said first key lever.
